[57] CLAIM

The ornamental design for a shot peen discharge nozzle, as shown.

DESCRIPTION

FIG. 1 is a perspective view of the shot peen discharge nozzle;

FIG. 2 is a side-view of said nozzle taken along line 2—2 of FIG. 6 with the upper surface of FIG. 6 on the right end of FIG. 2;

FIG. 3 is a side-view of said nozzle taken along line 3—3 of FIG. 5 with the upper surface of FIG. 5 on the left end of FIG. 3;

FIG. 4 is a side-view of said nozzle taken along line 4—4 of FIG. 6 with the upper end of FIG. 6 on the right end of FIG. 4;

FIG. 5 is an end-view of said nozzle from the left side of FIGS. 3 and 4; and,

FIG. 6 is an end-view of said nozzle from the right side of FIGS. 3 and 4.

The nozzle has been shown broken away in the center to show indeterminate length.
